(57) **CLAIM**

The ornamental design for the wind resistant plywood panel clip, as shown and described.

DESCRIPTION

FIG. 1 is a TOP view of a wind resistant plywood panel clip showing my new design;

FIG. 2 is a BOTTOM view thereof;

FIG. 3 is a FRONT view thereof;

FIG. 4 is a BACK view thereof;

FIG. 5 is a LEFT SIDE view thereof; and,

FIG. 6 is a RIGHT SIDE view thereof.

Figure titles represent the use of the wind resistant plywood panel clip on the left side of the plywood panel. This clip is reversible and may be used on the Top, Bottom, Left, or Right side of the plywood panel.
